UNITED STATES PATENT OFFICE

2,153,402

ELECTRIC SWITCH

John F. Tittle, Erie, Pa., assignor to General Electric Company, a corporation of New York

Original application September 29, 1937, Serial No. 166,277. Divided and this application June 30, 1938, Serial No. 216,790

7 Claims. (Cl. 200—10)

My invention relates to switches for controlling electric circuits and has for its object a simple and reliable arc extinguishing means for switches.

More particularly, my invention has for its object a switch provided with magnetic means for extinguishing the arc formed between the contacts of the switch.

This application is a division of my copending application, Serial No. 166,277, filed September 29, 1937, for Electric switch.

In carrying out my invention, I provide magnetic arc extinguishing means comprising a permanent magnet in the form of a straight bar which is mounted adjacent the fixed contact in position to effectively extinguish an arc formed between the contacts. This bar magnet is made of a material having a high coercive force. It operates to extinguish effectively the arc while being extremely simple and compact in construction.

This bar type arc-extinguishing magnet is of especial advantage where a plurality of switches are used. In accordance with my invention these switches may be mounted in side by side relation with an arc-extinguishing magnet consisting of a single bar extending adjacent the fixed contacts.

For a more complete understanding of my invention reference should be had to the accompanying drawing of which Fig. 1 is a plan view of a group of switches embodying my invention; Fig. 2 is a side view of the device shown in Fig. 1; Fig. 3 is a sectional view along the line 3—3 of Fig. 1, while Fig. 4 is a sectional view along the line 4—4 of Fig. 1, but showing the switch in the closed circuit position.

Referring to the drawing, I have shown my invention as applied to a group of manually operated switches which are identical in construction, four switches being shown, each being provided with an operating member 10. As shown in Fig. 3, the operating member 10 is made of a suitable electrically insulating material which preferably is a molded composition. It is provided with a projection or handle 11 which may be grasped to turn it about a pivot shaft 12 on which the member is mounted.

The member 10 is provided with a second projection 13 which, as viewed in Fig. 3, extends downward from a point adjacent the pivot shaft 12. This projection 13 engages the supporting base 14 when the operating member is in the open circuit position. On its lower end, the projection 13 is provided with a groove or recess 15 which forms a bearing for one end of the link member

16, the other end of which rests in a bearing seat 17 formed for it on the end of a cantilever spring 18. The other end of the spring is secured to the base 14 by means of a bolt 19. The link 16 and the projection 13 thus constitute a toggle, the 5 movable pivot point 15 between them moving from one side to the other of a line joining the center of the shaft 12 with the bearing 17 so as to thereby give the member 10 a snap action and hold the member 10 in either the open position 10 as shown in Fig. 3 or the closed position shown in Fig. 4.

The movable contact 20 of the switch is secured to the end of an electrically conducting strip 21 having near its center a loop or recess 22 formed 15 by bending it. This loop 22 forms a bearing for a projection 23 on the operating member 10. The strip 21 is secured in place by means of a pin 24 extending loosely through an aperture provided for it in the strip on the side of the loop 22 opposite the contact 20, and also loosely through an aperture provided for it in the operating member 10. A head 25 is provided on the pin, which head engages the strip 21 and furthermore forms a seat for one end of a helical spring 26, the other 20 end of which surrounds the head 27 of the bolt 19. A flexible conductor 28 connects the strip 21 with a short terminal strip 29 which is clamped to the base 14 by the bolt 19, the lower end of the spring 26 resting on this strip 29. In addition to 30 its other functions the bolt 19, which is preferably made of a suitable electrically conducting material such as steel or copper, serves as a terminal for the switch to which an electrical connection may be made.

The stationary contact 30 of the switch is mounted on a block 31 of electrical conducting and non-magnetic material such as brass or copper in position to be engaged by the movable contact 20, this block being in turn secured to a 40 terminal conductor or strap 32. Preferably as shown, the block 31 is formed integrally with the strap 32. The block 31 is furthermore provided with an aperture 33 for a rod or bar 34 made of a suitable magnetizable material and 45 serving as a magnetic blow-out device for the arc formed between the contacts 20 and 30.

The magnetic bar 34 is made of a material having a high coercive force preferably an alloy consisting mainly of aluminum, nickel and iron, 50 preferably aluminum 12%, nickel 25%, the balance being mainly iron, such as described and claimed in United States Patent No. 1,947,274, issued February 13, 1934, to William E. Ruder and United States Patent No. 2,027,994, issued 55

January 14, 1936 to Tokushichi Mishina. I have found that very effective blow-out action is obtained with a magnetized rod or bar of this material arranged as shown in the drawing near the 5 stationary contact, but on the side of the stationary contact opposite from the movable contact, and having its axis extending at right angles to the arc drawn between the contacts or as shown at right angles to the plane of movement 10 of the movable contact.

In the assembly of a plurality of switches as disclosed, the various blocks 31 forming the supports for stationary contacts are formed integrally with the supporting strap 32 and in suitable spaced relation with each other. Barriers or arc chute members 35 made of a suitable electrically insulating material, such as building lumber, are put in place between adjacent blocks and then the magnetized rod 34 is inserted in 15 the blocks and through suitable apertures provided for it in the arc chute members 35. An additional arc chute member 36 is provided at each end of this assembly, the rod 34 being long enough to extend through these two outer members. A rectangular pole piece member 37 made 20 of a suitable non-magnetizable magnetic material, such as magnet core iron, is secured against each end of the bar 34 by screws 38 which also secure the arc chute members 36. This assembly 25 is secured to the insulating base 14 by means of bolts 39 and 40 extending through the ends of the strip 32. As shown, the base 14 is cut away to leave a rectangular opening 41 for this assembly of the contacts, arc chutes and magnetized bar. One or both of the bolts 39 and 40 30 may be used as a common terminal for the switch, or terminals on the members 31 may be provided.

As shown, the operating members 10 are 40 mounted on a common pivot bar 12 which is secured by means of one or more brackets 42 to the base 14 in suitably spaced relation thereto.

Obviously more than four switches can be secured together in a group and I have in fact 45 disclosed for purposes of illustration one end only of an assembly of several groups of these switches.

In the operation of the switch it will be observed that the supporting strip 21 for the movable contact is held in place by the helical spring 50 26 and furthermore when the movable contact engages the stationary contact the spring 26 yields to provide for pivot movement of the strip on the projection 23 in a clockwise direction as 55 seen in Fig. 3, the strip coming to rest against the outer end of the member 10, as shown in Fig. 4. This movement of the movable contact provides for a wiping action on the stationary contact whereby a good electrical engagement 60 between the contacts is assured. To further provide for this wiping action the cantilever spring 18 is constructed to apply a greater force to the member 10 tending to close it than the force applied in the opposite direction by the 65 spring 26.

It will be understood that the member 10 is 70 forcibly moved by means of the handle 11 in both the opening and closing directions through an angle sufficient to bring the pivot point 15 to the other side of the toggle straightened position whereby the force exerted by the spring 18 is reversed and the opening or closing movement of the switch is completed by the spring 18.

The pivot movement of the strip about the 75 projection 23 is furthermore somewhat greater

than the movement of the member 10 required to reverse the force supplied by the spring 18 and consequently the contacts are separated by the snap action thereafter produced by the snap spring 18. 5

While I have shown a particular embodiment of my invention, it will be understood, of course, that I do not wish to be limited thereto since many modifications may be made, and I therefore contemplate by the appended claims to cover 10 any such modifications as fall within the true spirit and scope of my invention.

What I claim as new and desire to secure by Letters Patent of the United States is:

1. The combination with a switch provided 15 with cooperating movable and stationary contacts, said movable contact being mounted for movement in a predetermined plane, of a substantially straight bar shaped permanent arc extinguishing magnet adjacent said stationary 20 contact extending in a direction substantially at right angles to said plane of movement, said magnet being made of a material having a high coercive force consisting mainly of aluminum, nickel, and iron. 25

2. The combination with a plurality of switches each provided with a stationary contact and a cooperating movable contact, of a substantially straight permanent magnet mounted adjacent 30 said stationary contacts in position effectively to extinguish arcs formed between said cooperating stationary and movable contacts.

3. The combination with a plurality of switches each provided with a plurality of pairs of cooperating movable and stationary contacts, said 35 stationary contacts being arranged substantially in alignment with each other and said movable contacts being mounted for movement in substantially parallel planes, of a continuous arc extinguishing permanent magnet extending adjacent said stationary contacts in a direction substantially at right angles to said planes of movement, and a common support made of electrically conducting non-magnetic material for said stationary contact and said permanent magnet. 40

4. The combination with a plurality of switches each provided with cooperating movable and stationary contacts, said stationary contacts being arranged substantially in alignment with each 50 other and said movable contacts being mounted for movement in substantially parallel planes, of a continuous bar arc extinguishing permanent magnet adjacent said stationary contacts, said magnet being made of a material having a high 55 coercive force consisting mainly of aluminum, nickel and iron and a common support made of electrically conducting non-magnetic material for said stationary contacts and said permanent magnet. 60

5. An electric switch comprising a plurality of stationary contacts, a support for said contacts made of electrically conducting non-magnetic material, a substantially straight permanent magnet mounted on said support, and a plurality of movable contacts cooperating with 65 said stationary contacts and mounted for movement in planes substantially at right angles to said permanent magnet. 70

6. An electric switch comprising a plurality 70 of stationary contacts, a support for said contacts made of electrically conducting material, said support being provided with an aperture, a substantially straight permanent magnet extending through said aperture, and a plurality of 75

movable contacts cooperating with said stationary contacts and mounted for movement in planes substantially at right angles to said permanent magnet.

- 5 7. An electric switch comprising a plurality of blocks made of electrically conducting material, means securing said blocks together in spaced relation with each other, a stationary contact secured to each of said blocks, said contacts being in alignment with each other, each of said blocks being provided with an aperture closely adjacent its contact and said apertures

being in alignment with each other, a plurality of arc barriers between said blocks, said arc barriers being provided with an aperture, a permanent magnet extending through the apertures in said blocks and through the apertures in said arc barriers so as to hold the arc barriers in a predetermined relation with said blocks, and a plurality of movable contacts cooperating with said stationary contacts and mounted for movement in planes substantially perpendicular to 10 said permanent magnet.

JOHN F. TRITTLE.
